[57] CLAIM

The ornamental design for a coffee filter holder, as shown and described.

DESCRIPTION

FIG. 1 is a front elevational view of the coffee filter holder of the present invention;

FIG. 2 is a back elevational view of the coffee filter holder of FIG. 1;

FIG. 3 is a left side elevational view of the coffee filter holder of FIG. 1;

FIG. 4 is a right side elevational view of the coffee filter holder of FIG. 1;

FIG. 5 is a top plan view of the coffee filter holder of FIG. 1; and,

FIG. 6 is a bottom plan view of the coffee filter holder of FIG. 1.

The broken lines showing coffee filters in FIGS. 3 and 4 are for illustrative purposes only and form no part of the claimed design.
